J. M. JOHNSON

CIGAR LIGHTER

Filed Sept. 17, 1920

FIG. 1.

FIG. 2.

FIG. 3.

FIG. 4.

Witness:

Bud L. Fischer.

Inventor:
John M. Johnson,

By F. G. Fischer, atty.

UNITED STATES PATENT OFFICE.

JOHN M. JOHNSON, OF KANSAS CITY, MISSOURI.

CIGAR LIGHTER.

Application filed September 17, 1920. Serial No. 410,916.

To all whom it may concern:

Be it known that I, JOHN M. JOHNSON, a citizen of the United States, residing at Kansas City, in the county of Jackson and 5 State of Missouri, have invented certain new and useful Improvements in Cigar Lighters, of which the following is a specification.

My invention relates to cigar lighters and 10 one object is to provide a device of this character embodying a torch and electrical means for igniting said torch.

A further object is to provide a cigar lighter of simple construction and but few 15 movable parts, so that it will not likely get out of order.

Other objects will hereinafter appear, and in order that the invention may be fully understood, reference will now be had to 20 the accompanying drawing, in which:

Fig. 1 is a side elevation of the device.

Fig. 2 is a central vertical sectional view of the device.

Fig. 3 is a plan view of the device.

25 Fig. 4 is a cross section on line IV—IV of Fig. 2.

In carrying out the invention, I employ a stand 2 made, preferably, of cast metal and embodying a bell-shaped base 4 and a 30 central, upwardly-extending, tubular fount or reservoir 6 adapted to hold an inflammable liquid such as alcohol, benzene, etc. The upper end of the fount 6 is closed by a screw cap 8, having a central bore in which 35 the upper end of a tube 10 is fixed. Said tube 10 extends downwardly to within a short distance of the bottom of the fount 6 and is provided with a wick 12 for conducting the inflammable liquid upwardly to a 40 torch 14.

The torch 14 consists of a handle 16, a tubular stem 18 depending from said handle 16, and a wick 20 arranged in the lower portion of said stem 18. The handle 16 consists 45 preferably of rubber or other insulating material, while the stem 18 consists preferably of brass and is small enough in diameter to readily enter the tube 10. The wick 12 extends upwardly to the wick 20 50 as disclosed on Fig. 2 to conduct the inflammable liquid to said wick 20.

The bottom of the base 4 is closed by a spool 22 which is secured to said base 4 by suitable means such as screws 24. The un- 55 derside of the spool 22 and the bottom of

the base 4 are covered with a felt or other cushion 26 to protect the finish on the counter or other support upon which the stand 2 may be placed.

The spool 22 is equipped with a choke 60 coil 28, one terminal of which is connected to an electrode 30 while the opposite terminal is connected to a plug 32 adapted to be screwed into an incandescent lamp socket or other suitable source of electrical energy. 65 A wire 34 leads from the plug 32 to another electrode 36 disposed adjacent to the electrode 30.

The terminals 30 and 36 are fixed in metallic nipples 38 and 40, respectively, which 70 in turn are fixed in a plug 42 of fibre or other insulating material which is screwed into or otherwise fixed to the base 4. A rubber or other insulated bushing 44 extends through the base 4 to thoroughly insulate 75 the wires 28 and 34 from said base. The wires are also covered with insulating material to prevent possible shock to the user of the device.

In practice the fount 6 is provided with 80 inflammable liquid, which saturates the wicks 12 and 20, and the plug 32 is connected to a lamp socket or other source of electricity. When a light is desired the torch 14 is grasped by its handle 16 and 85 drawn across the electrodes 30 and 36 to produce a spark for igniting the saturated wick 20. After the user is through with the light, the torch 14 is replaced in the tube 10 which operation extinguishes the 90 flame at the wick 20. The device will operate with either an A. C. or D. C. current, and where the voltage is low the choke coil 28 may be dispensed with.

From the foregoing description it will be 95 readily understood that I have produced a cigar lighter embodying the advantages above pointed out, and while I have shown and described the preferred construction of the invention, I reserve the right to make 100 such changes as properly fall within the spirit and scope of the claim.

Having thus described my invention, what I claim and desire to secure by Letters Patent, is:

A device of the character described consisting of a stand having a bell-shaped base and a central fount projecting upwardly from said base, a cap threaded in the upper end of said fount and having a central bore, 110

a tube fixed at its upper end in the bore of said cap and terminating at its lower end adjacent to the lower end of the fount, a wick in the lower portion of said tube for absorbing an inflammable liquid in the fount, a torch adapted to be inserted in the tube and provided at its lower end with a wick to contact the first-mentioned wick, and a handle at its upper end which rests

upon the cap and supports the torch, substantially as shown and described.

In testimony whereof I affix my signature, in the presence of two witnesses.

JOHN M. JOHNSON.
